JOSEPH C. WELLS, SR., OF ESSERVILLE, VIRGINIA, ASSIGNOR OF ONE-HALF TO W. D. HATFIELD, OF ESSERVILLE, VIRGINIA.

COUPLING.

1,391,597.

Specification of Letters Patent. Patented Sept. 20, 1921.

Application filed June 4, 1920. Serial No. 386,421.

To all whom it may concern:

Be it known that I, JOSEPH C. WELLS, Sr., a citizen of the United States, residing at Esserville, in the county of Wise and 5 State of Virginia, have invented new and useful Improvements in Couplings, of which the following is a specification.

This invention relates to railway rolling stock, particularly to car couplers, and has 10 for its object the provision of an automatic coupling device so constructed that when two cars are brought together the coupling members carried by each will be automatically interengaged without the necessity for 15 any manual operation whatever.

An important object is the provision of 20 a device of this character in which the coupling members are provided with manually operable means whereby they may be quickly and easily disengaged to effect uncoupling of the cars.

An additional object is the provision of 25 a device of this character which will be simple and inexpensive in manufacture and installation, easy to operate, efficient in use, durable in service, and a general improvement in the art.

With the above and other objects and advantages in view, the invention consists in 30 the details of construction to be hereinafter more fully described and claimed, and illustrated in the accompanying drawings in which:—

Figure 1 is a side elevation of the device 35 showing two of the coupling members carried by adjacent ends of cars engaged, only fragments of the ends of the cars being shown.

Fig. 2 is an enlarged longitudinal sectional view showing them engaged.

Fig. 3 is a cross sectional view.

Referring more particularly to the drawings, the letter A designates the end portions of cars arranged in end to end relation. 45 In carrying out my invention I provide a draw bar 10 pivotally connected or mounted upon each car in the ordinary manner or by any desired special means. Each draw bar 10 is formed with a head having a longitudinally extending recess 11 having a flaring entrance opening to define an inclined shoulder 12, and is furthermore formed in its bottom, with an elongated slot 13 leading into the recess 11.

55 Extending longitudinally of and project-

ing beyond the free end of each draw-bar head 10 is a coupling bar 14 formed, in the present instance, as a loop-shaped bar or a bar having a longitudinal slot 15. This bar is located within a groove 16 formed in 60 the bottom of the draw-bar. At a point spaced considerably from the end of the draw-bar the bar 14 is pivoted upon a transverse pin 17 and the extremity of the bar engages against one end of a coil spring 18 65 extending within a vertical socket 19 in the draw-bar. By this construction the spring 18 will operate to hold the coupling bar in position ready to engage a mating member.

Between the pin 17 and the free end of 70 the draw-bar is disposed a substantially vertical arm 20 which is pivoted upon a transverse pin 21 and this arm extends across the recess 11 and has its free end operable through the slot 13, the end of the arm being 75 engageable with the end of the slot toward the free end of the head. The arm 20 is right angular in shape so as to provide a substantially horizontal portion 22 disposed in spaced parallel relation to the top 80 of the head and connected with the free end of this arm portion 22 is a tension spring 23 which is connected with the top of the head by any desired means and which operates to hold the arm 20 in engagement 85 with the forward end of the slot 13.

In order that the arm 20 may be moved out of engagement with the end of the slot 13, I provide an angular lever 24 which is pivoted upon the pin 21 and which includes 90 a hand engaging portion 25 which normally extends substantially vertically above and at one side of the head and which further includes a substantially horizontal portion 26 disposed adjacent the head and engageable 95 with the arm 20.

In the carrying out of the invention the draw-bars on adjacent cars are arranged in the same relation, as clearly shown, the coupling bars 14 both being at the bottom of 100 the heads. With the heads arranged in this manner, it will be seen that when two cars are brought together and the heads arranged in alinement, the projecting end of one coupling bar 14 will enter the flaring end of 105 the recess 11 in the other head engaging against the inclined shoulder 12. As the cars are then moved together the coupling bar 14 will ride upon the shoulder 12 until it engages the arm 20. Continued movement 110

of the cars will result in swinging movement of the arm 20 so that the coupling bar will ride thereunder and beyond it until the ends of the heads contact. As soon as the 5 coupling 14 passes under the arm the arm will swing so that the free end thereof will pass into the slot 13 of the draw-bar and will return by virtue of the spring 23, to normal position engaging the end of the slot 13. It 10 will be observed that the cars will then be efficiently coupled together. Only one coupling bar enters the opposite head, the other coupling bar being inoperative and being in reserve ready for use in case one coupling 15 bar is broken.

When it is desired to uncouple the cars it is first necessary that the cars be moved to bring the coupler heads close together, after which it is merely necessary that the operator 20 grasp the hand portion 25 of the lever 24 engaging the arm 20 in use and swing it toward the meeting point of the heads, whereupon the horizontal portion 26 of the lever engaging the projecting end of the arm 25 20 will swing the arm so that it will be withdrawn from the slot 13 whereupon there will be nothing engaging the coupling bar and the cars may be separated.

From the foregoing description and a 30 study of the drawings it will be apparent that I have thus provided a comparatively simple and inexpensive coupling device for

railway cars or in fact any other wheeled vehicle, the coupling action of which will be entirely automatic and accomplished merely 35 by bringing the cars together.

While I have shown and described the preferred embodiment of my invention, it is of course to be understood that I reserve the right to make such changes in the form, 40 construction, and arrangement of parts as will not depart from the spirit of the invention or the scope of the subjoined claim.

Having thus described my invention, I 45 claim:

A coupling of the character described comprising similar members carried by the adjacent ends of cars, each member including a head having a longitudinal recess with a flaring entrance, a swing pin within each recess, a coupling link pivoted intermediate its ends upon the lower side of the head and having one end extending beyond the head and upwardly offset whereby the coupling link of either head may be positioned to enter the recess of the other head, the head being formed in its underside with a recess spaced from the first named recess, and a spring within the second named recess engaging the coupling link whereby to hold 55 the latter normally against the underside of the head.

In testimony whereof I affix my signature.
JOSEPH C. WELLS, SR.
